DESIGN FOR A COMBINED WHEEL DISK AND HUB CAP, OR SIMILAR ARTICLE

George Albert Lyon, Allenhurst, N. J.

Application December 19, 1934, Serial No. 54,490

Term of patent 14 years

To all whom it may concern:

Be it known that I, George Albert Lyon, a citizen of the United States and a resident of the city of Allenhurst, in the county of Monmouth and State of New Jersey, have invented a new, original, and ornamental Design for a Combined Wheel Disk and Hub Cap, or Similar Article, of which the following is the specification, reference being had to the accompanying drawing, forming a part thereof.

On the drawing:

Figure 1 is an outer side view of a combined

wheel disk and hub cap embodying my design.

Figure 2 is a side elevational view of the combined wheel disk and hub cap shown in Figure 1, and including a section so as to show the contour of the outer portion of the disk.

Figure 3 is a profile view showing in outline form the contour of my novel design.

I claim:

The ornamental design for a combined wheel disk and hub cap, or similar article, as shown.

GEORGE ALBERT LYON.
